CLAIM

The ornamental design for a cap for a pouch, as shown and described.

DESCRIPTION

FIG. 1 is a top perspective view of a cap for a pouch of the present invention;

FIG. 2 is a front perspective view of the cap for a pouch of FIG. 1;

FIG. 3 is a side perspective view of the cap for a pouch of FIG. 1;

FIG. 4 is a front view of the cap for a pouch of FIG. 1;

FIG. 5 is a left view of the cap for a pouch of FIG. 1;

FIG. 6 is a back side view of the cap for a pouch of FIG. 1;

FIG. 7 is a right side view of the cap for a pouch of FIG. 1;

FIG. 8 is a top view of the cap for a pouch of FIG. 1;

FIG. 9 is a bottom view of the cap for a pouch of FIG. 1;

FIG. 10 is a perspective view of the cap of FIG. 1 for a pouch;

FIG. 11 is a front view of the cap for a pouch of FIG. 10;

FIG. 12 is a left view of the cap for a pouch of FIG. 10;

FIG. 13 is a back side view of the cap for a pouch of FIG. 10;

FIG. 14 is a right side view of the cap for a pouch of FIG. 10;

FIG. 15 is a top view of the cap for a pouch of FIG. 10; and,

FIG. 16 is a bottom view of the cap for a pouch of FIG. 10.

In the drawings, the broken lines show portions of a cap for a pouch that form no part of the claim: In FIGS. 10–18, the broken lines also depict a pouch that forms no part thereof.

1 Claim, 11 Drawing Sheets
